ROTARY SIDE HEAT SEALER FOR
PACKAGES

Victor George Williams, Toronto, Ontario, Canada, assignor, by mesne assignments, to Delamere & Williams Company, Limited, Toronto, Ontario, Canada

Application December 26, 1947, Serial No. 793,945

3 Claims. (CL. 154—42)

1

This invention relates generally to heat sealing machinery, and more particularly to a rotary heat sealer for the sealing of tea bags or similar packages along their vertical sides.

An object of this invention is to provide means for substantially continuous or regular sealing of the vertical sides of packages, thereby obviating the necessity of reciprocating action.

The foregoing and still further objects will become apparent from a study of the following specification, taken in conjunction with the accompanying drawings, wherein like characters of reference indicate corresponding parts throughout the several views and wherein

Figure 1 is a vertical side view of a portion of a tea bagging machine showing in particular the outside heat sealing roller of the pair of sealing rollers.

Figure 2 is a horizontal section of the side sealing rollers on the line 2—2 in Figure 1.

Figure 3 is a vertical section taken through the axes of rotation of the side sealing rollers on the line 3—3 of Figure 1. Among other things, are shown here the air cylinder and associated lever mechanism for bringing the rollers into contact with the opposite sides of the bags to be sealed.

The construction of side sealing mechanism hereinafter fully described, is an improved construction over than disclosed in United States patent application No. 713,668 filed December 3, 1946, now Patent No. 2,556,382, applicants V. G. Williams et al., wherein the sealing of the vertical sides of the bags was accomplished by reciprocating action of heated elements rather than by the continuous rotation of heated ribbed rollers.

For an extensive description of the entire tea bagging machine, reference is made to the above mentioned United States application. However, for purposes of understanding this particular construction of rotary side sealing mechanism, a brief description of the entire machine follows.

The paper or other material from which the tea bags are formed is obtained in the form of a roll, one side of the paper carrying a thin non-toxic thermoplastic, which acts as an adhesive when subjected to a comparatively high temperature. The strip of paper as it unrolls passes through a plurality of fingers which form it into a V-shaped channel, the adhesive coated surface being on the inside. Pairs of spring loaded fingers then close upon the paper, producing a plurality of individual pockets, into which is poured the desired quantity of tea. Just prior to the filling

2

of the pockets, the originally continuous strip of paper is sheared transversely of its direction of movement at points between successive pockets, thereby producing individual, separated receptacles for the tea.

The individual tea bags, their vertical edges supported by the spring loaded fingers, then pass along a track between the rotary side sealing rollers, which seal the opposite sides of the bags or containers along the edges produced by the shears. Following the sealing of the sides of the bags, the bags pass between the top sealing rollers, where they are completely closed. The fingers supporting the bags then release them, and the bags are removed and ultimately deposited in a suitable receptacle.

The construction of the vertical side sealing rollers will now be described in detail, with reference to all the figures.

20 An outside roller 4 is bolted to spindle sleeve 5 which in turn is affixed to shaft 6. Loading on this shaft is taken by tapered roller bearings 7 and 8, and by housing 9.

Roller 4 which in the preferred construction 25 is of Monel metal, is heated to a suitably high temperature by an electrically insulated resistance element 10 self supported in the form of a coil within the roller, but mechanically independent of rotation of the latter. The head of roller 4 is provided with an axial cavity 11 into which thermostat 12 extends. Thermostat 12 is supported upon bracket 12^a and is adapted to control the temperature of the sealing roller in a well known manner which is not shown since it does 30 not form part of this invention.

Disposed upon the periphery of drum 4 in planes parallel to the axis of rotation of the roller are a plurality of equally spaced ribs 13, the purpose of which will be subsequently described.

40 An inner roller 14 carrying bearings 15, 15, rotates upon axle 16 which is fixed to carriage 17. Disposed upon the periphery of roller 14 are a plurality of ribs 18 which correspond in number 45 and placement to the ribs 13 on roller 4. The outer surfaces of ribs 18 carry retaining grooves 19 running longitudinally of the ribs. Resilient members 20 are supported upon the outer surfaces of ribs 18 by means of tongues 21 which are gripped by grooves 19. In the preferred construction resilient members 20 are made of neoprene, a synthetic rubber which withstands high temperatures and pressures, without losing its elasticity or shape. Rotation of inner drum 14 is 50 synchronized with that of outer drum 4 by means 55

of gears 22 and 23, so that bearing surfaces 24 and 25 of resilient rib members 20 and ribs 13 respectively, co-act and press firmly together, transversely of the direction of movement of the carrier, against opposite sides of the containers to be sealed.

The degree of pressure which is exerted upon each rib by the corresponding rib on the other roller is determined by the spacing of the axles 6 and 16 supporting the rollers. The former rests upon bearings 7 and 8 within housing 9, so that it is capable only of rotation, whereas the latter rests upon bearings which are attached to carriage 17 and therefore is capable of translation as well as of rotation. Carriage 17 reciprocates horizontally upon bed 26 in a plane containing the axes of rotation of rollers 4 and 14, so as to vary the spacing between the two axes.

The actual position of carriage 17 upon bed 26 is controlled by an air cylinder 27 and an associated lever mechanism designated generally as 28. When the packaging machine is in operation, air pressure is supplied through pipe 29 to flexible coupling 30 which couples to the trunnion type air cylinder 27, pivoted at 31. An application of air pressure compresses spring 32 causing roller 14 to move toward roller 4. Since air pressure exists only when the machine is in actual operation, the rollers will automatically separate should the machine stop, thereby preventing the overheating of the neoprene or other resilient material on the inner roller.

Although the magnitude of the air pressure could be used to control the pressure exerted between the co-acting ribs of the rollers, this is not done in practice. It has been found to be more satisfactory to use a high pressure to force the carriage against an adjustable stop 33, the position of the stop thereby acting to control or limit the pressure exerted at the surfaces of the ribs.

The actual position of the synchronized ribs on the two rollers also must be adjusted carefully with respect to the fingers of the bag carrier system, so that sealing of the vertical edges of the bags will be accomplished accurately. Before the bags enter the space between the vertical or side sealing rollers they have been filled with the desired amount of tea or other substance and have also been separated into individual bags, the material remaining in the bags only by virtue of the pairs of fingers 38 gripping both edges of the bag along its entire depth. Due to the fact that the bags are travelling in a substantially straight line as they pass between the vertical side sealing rollers, the edges of successive bags frequently touch or even overlap slightly. If the sealing ribs were pressed indiscriminately upon the edges of the bags, any that were at that instant overlapped would be sealed firmly together, necessitating manual separation. In order to eliminate this trouble, small knife like projections 34 are provided, running longitudinally of the centre of the sealing surface 25 of each of ribs 13. In each sealing surface 24 of resilient members 20 running longitudinally of the surface along its centre is a corresponding slot 35 into which the projection 34 will pass.

Projection 34 and slot 35 co-operate during the sealing process to separate the edges of successive bags from each other, preventing their being sealed together, as shown clearly in Figure 2. Since the bags are being carried in the direction indicated by arrow 36, the bags are shown sep-

arated, having just previously been sealed adjacent their edges 36 and 37. Thus projections 34 and grooves 35 allow each co-operating pair of ribs to seal the adjacent edges of two successive containers simultaneously, and eliminate an otherwise duplex operation.

It will be noted that the height of the ribs on the rollers must be sufficiently great that the recesses formed between adjacent ribs on the same roller will not interfere with the bags or carrier fingers as they pass between the rollers.

It is thought that the construction and use of the invention will be apparent from the above description of the various parts and their purposes. It will be apparent that changes can be made in the arrangement, shape, or size of the various components shown without departing from the fundamental principles upon which the present invention is based, as defined in the subjoined claims.

What I claim as my invention is:

1. In a packaging machine of the character described, heat sealing means comprising a pair of cooperating rollers operatively connected together mounted with their axes in parallel relation and provided at spaced intervals around the cylindrical surface thereof with sealing ribs disposed in parallel relation to the axes of the rollers, for sealing engagement with the material advanced therebetween, means for rotating said rollers so that the ribs cooperate with each other during rotation of the rollers, one of said rollers being heated, the other roller being mounted for movement toward and away from said one roller, pneumatically operated means operative only during rotation of the rollers for moving said movable roller into sealing engagement during the operation of the machine, and resilient means arranged to automatically maintain the rollers separated when rotation of the rollers and operation of said pneumatically operated means is discontinued, said roller mounting including a slideable carriage, and stop means engageable with the carriage for limiting the movement of said movable roller towards the heated roller.

2. In a packaging machine of the character described, heat sealing means comprising a pair of cooperating rollers operatively connected together mounted with their axes in parallel relation and provided at spaced intervals around the cylindrical surface thereof with sealing ribs disposed in parallel relation to the axes of the rollers, for sealing engagement with the material advanced therebetween, means for rotating said rollers so that the ribs cooperate with each other during rotation of the rollers, one of said rollers being heated, the other roller being mounted for movement toward and away from said one roller, pneumatically operated means operative only during rotation of the rollers for moving said movable roller into sealing engagement during the operation of the machine, and resilient means arranged to automatically maintain the rollers separated when rotation of the rollers and operation of said pneumatically operated means is discontinued, said roller mounting including a slideable carriage, and said pneumatically operated means including an air cylinder and a piston operatively connected to said carriage.

3. In a packaging machine of the character described, heat sealing means comprising a pair of cooperating rollers operatively connected together and mounted with their axes in parallel relation and provided at spaced intervals around the cylindrical surfaces thereof with sealing ribs

disposed in parallel relation to the axes of the rollers for sealing engagement with adjacent edges of a series of successive individual non-connected containers advanced therebetween, means for rotating said rollers so that the ribs cooperate with each other during rotation of the rollers, said cooperating ribs being arranged to effect simultaneous sealing of the trailing edge of one container and the leading edge of a succeeding and closely adjacent separate container, each of the ribs of one roller having a medial longitudinal projection having a crest surface of substantial width and length and the crests of the ribs of the second roller comprising blocks of resilient material each having a corresponding slot for co-operation with a respective projection and arranged to fold portions of said closely adjacent edges into said slot to separate said edges during a sealing operation thereby to prevent sealing of said adjacent edges one to the other.

VICTOR GEORGE WILLIAMS.
